J. P. KING

CARRIER FOR BRAIDING MACHINES

Original Filed Jan. 6, 1922

UNITED STATES PATENT OFFICE.

JOHN P. KING, OF PROVIDENCE, RHODE ISLAND, ASSIGNOR, BY DIRECT AND MESNE ASSIGNMENTS, TO IDEAL BRAIDING MACHINE COMPANY, A CORPORATION OF RHODE ISLAND.

CARRIER FOR BRAIDING MACHINES.

Application filed January 6, 1922, Serial No. 527,381. Renewed December 1, 1922.

To all whom it may concern:

Be it known that I, JOHN P. KING, a citizen of the United States, residing at Providence, in the county of Providence and 5 State of Rhode Island, have invented certain new and useful Improvements in Carriers for Braiding Machines, of which the following is a specification.

This invention relates to improvements in 10 the construction of carriers for braiding machines, and has for its object to provide such a carrier which is particularly adapted for running at a high velocity, being of a very strong and durable construction and yet 15 light in weight, the operating parts of the carrier being mounted to properly control the let off of the yarn or thread while running at a high rate of speed. This case is a continuation in part of my former abandoned case, Serial No. 347,278, filed Dec. 26, 20 1919.

With these and other objects in view, the invention consists of certain novel features of construction, as will be more fully described, and particularly pointed out in the appended claims.

In the accompanying drawings,

Figure 1 is a side elevation partly in section showing the construction of my improved carrier.

Figure 2 is a perspective view of the weight-carrying standard member looking from the rear and showing a slot in its front, side and rear walls by means of 35 which slots the latch may be guided when in operative position, and also removed from the standard when desired.

Figure 3 is a perspective view of the latch member showing the feed-controlling finger 40 mounted on its spindle.

Figure 4 is a perspective view looking at the inner side of the bottom weight.

Figure 5 is a perspective view of the base member of the carrier.

45 Figure 6 is a perspective view of the carrier standard supporting member.

Figure 7 is a view of the rear of the carrier showing the supporting projection on the bottom weight as entering the complementary slot in the base member to support the weight against the shock of engaging and throwing the stop mechanism.

With reference to the drawings, 10 designates the base portion of the carrier, which 55 is provided with a longitudinal rib 11, bored

at 12 for the reception of a spindle 13 on which is rotatably mounted a yarn package carrying spool 14.

Instead of forming the weight-standard integral with the base member I preferably 60 provide a standard 15 formed by folding comparatively thin sheet metal into a combined tubular and trough shape, the back of the lower portion being open or in trough shape while the upper portion of the stand- 65 ard is in tubular shape.

The front wall of this upper tubular portion is slotted vertically as at 16 to permit the feed-controlling finger of the latch member 17 to slide vertically therein and this 70 standard is slotted through its side wall as at 18 to permit this latch finger when lifted out of its guide slot to be swung on the axis of its spindle 9 to permit the removal of the package, and the rear wall of this 75 standard is provided with a narrow slot 19 to permit the passage of the reduced portion 20 of the finger to pass therethrough when it is desired to swing this portion to the rear to drop it through this slot for the purpose 80 of removing the latch for inspection or repairs.

In this upper tubular end of the standard I have preferably mounted a phosphor bronze or anti-friction bushing 20' which is 85 bored at 21 to receive the upper end of the spindle 9 and also to receive a spring 22 for exerting a downward tension on the latch, the upper end of this spring being secured to the reduced neck portion of the screw 23 90 whereby the spring may be readily removed by simply backing out the screw. The body of this bushing member 20' is arranged to extend down into the tubular portion of the standard below its front slot to also provide a lower bearing 24 for the latch spindle 9, and the upper portion of this bushing above the standard is provided with a laterally-extending head 25 in which a suitable thread guide 26 is mounted. 95

In order to rigidly attach this standard to the body portion of the carrier I first form a carrier standard supporting member 27 of sheet stock the same being forked as at 28 at its lower end to straddle the rib 11 100 and be riveted thereto, and to the upright projecting portion 29 of this support is riveted as at 30 the standard 15. 105

In order to further support the lower end of this standard I have provided an upward- 110

5 by extending boss 31 on the base which projects into the lower end of the standard to firmly support it which is of advantage particularly when the bottom weight engages

5 the stop motion.

10 The lower portion of this standard member is provided with laterally-extending guide flanges 32 on which is slidably mounted the bottom yarn tensioning weight 33.

15 This weight is also preferably formed of sheet stock having laterally-extending wings 34 folded to provide inwardly-turned lips 35 to slidably engage the flanges 32 and to also engage and operate the usual stop motion when the yarn breaks, and the upper

20 end of this weight is provided with an inwardly-turned tongue 36 to engage the latch spindle 9 and cause the latch to function when the weight is lifted sufficiently. The

25 lower end of this weight is provided with a downwardly-extending finger 37 adapted to extend into the notch 38 formed in the rear of the body portion for the purpose of firmly supporting the weight member upon receiving a shock of contact with the stop motion when this weight drops into stop position, and by this construction it will be seen that the shock of engagement with the stop motion is taken by the body member instead of

30 by the standard member as would otherwise be the case.

35 In order to effect a quick return action of this bottom weight after having been lifted by the thread tension during the rapid running of the carrier, I have provided a spring 39, the upper end of which is connected to the hollow stud 40 in this weight which also serves as a guide eye for the thread, while the lower end of this spring is connected to the stud 41 fixed to the

40 standard.

45 In this standard I have provided the usual guide eye 42 which cooperates with that in the weight to lift the latter into engagement with the latch causing it to function by the tensioning of the thread, but it is found in practice where the carrier runs very rapidly and where the thread is led directly from the package through this

50 guide 42 to the guide eye in the weight, that the sharp upward angle of the yarn when leading from the bottom of the package, has a tendency to lift the package and so prevent its proper functioning.

55 Therefore in order to obviate this serious difficulty I have provided a laterally-extending arm 43 on the carrier standard supporting member in which is located a guide eye 44. This auxiliary guide eye is

60 located in the standard and offset laterally therefrom towards the delivery side of the supply package thereby effectually reducing the angle of pull and likewise the lifting effect on the package as the yarn is rapidly drawn therefrom.

65 It will be seen by my improved construction of providing upper and lower bushings for the latch spindle that the same is well guided against cramping while in action; then again by providing a phosphor bronze bushing or bearings for this rapidly acting latch that it is further prevented from wearing even with the minimum amount of lubrication; and third, by providing a spring to insure rapid action of the latch and also another spring to insure rapid action of the bottom weight the yarn let off is properly controlled even when the carrier is running at a very high rate of speed.

70 75 80 Further, it will also be noted that by slotting the standard through its side wall that the latch finger when lifted from its front guide slot may rest upon the edge of this side wall during the removal and replenishing of the exhausted package.

85 90 The foregoing description is directed solely towards the construction illustrated, but I desire it to be understood that I reserve the privilege of resorting to all the mechanical changes to which the device is susceptible, the invention being defined and limited only by the terms of the appended claims.

95 I claim:

100 105 110 115 120 125 130 1. In a braider carrier, a base member, a weight-carrying standard formed of sheet metal folded into trough shape for a portion of its length with weight-guiding flanges, means for securing said standard to said base, a spring pressed latch having a feed-controlling finger and said latch having sliding bearings in said standard both above and below said finger, and a weight slidable on said guide flanges to engage and cause said latch to function by the tension of the thread.

110 115 120 125 130 135 140 2. A braider carrier comprising a base member having a weight standard formed of sheet metal folded into trough shape for a portion of its length with guide weight flanges, a standard supporting member on said base to which said standard is secured, a latch member in said standard, and a weight slidably mounted on said flanges to engage and cause said latch to function.

140 145 150 155 160 165 170 3. A braider carrier comprising a base member having a standard, a weight and a latch slidably mounted on said standard, a thread guide in said weight, a thread guide in said standard to control the lifting action of said weight upon said latch as tension is applied on the thread, and a second fixed thread-guide located below that in the standard and through which the thread is first led from the package to minimize its lifting effect on the package.

170 175 180 185 190 195 200 4. A braider carrier comprising a base member having a standard, a weight and a latch slidably mounted on said standard,

- a thread guide in said weight, a thread guide in said standard positioned to control the lifting action of said weight upon said latch as tension is applied on the thread, 5 and a second fixed thread guide located below that in the standard and offset laterally towards the delivery side of the supply package to reduce the lifting effect on the package as the yarn is drawn therefrom.
- 10 5. A braider carrier comprising a base member having a supply package spindle, a tubular standard supported on said base, a latch pivotally supported to swing laterally in said tubular standard from operative to 15 inoperative position to permit the removal of the supply package from its spindle.
6. A braider carrier comprising a base member having a supply package spindle, a tubular standard slotted through its front 20 and one side wall, a latch having a guide pin pivotally mounted in said standard and adapted to be swung from operative position into said side slot to rest upon the wall thereof and so be retained in position to permit 25 the removal of the supply package from its spindle.
7. A braider carrier comprising a base member having a supply package mounted thereon, a hollow weight carrying standard 30 being slotted in its front, side and rear walls, a package feed controlling latch pivotally mounted in said standard and adapted to extend through and be guided in said front slot when in engagement with the package 35 and to be lifted from said front slot, swung through said side slot and dropped through said rear slot to be removed from said standard.
8. A braider carrier comprising a latch fixed to a slidable guide pin, a spring above 40 said latch assisting it to function, in combination with a cooperating bottom weight positioned to engage and lift said pin and latch, and a spring below said weight exerting a downward tension thereon causing it to function in unison with said latch after having raised the same. 45
9. A braider carrier comprising a base member having a weight standard, a feed-control latch operatively mounted on said standard, a tension weight slidably mounted on said standard, and cooperating interlocking means on said weight and base arranged to engage each other when the weight drops to stop position to assist in supporting the 50 weight against the lateral thrust of the stop motion and to be lifted from such engagement when the weight rises. 55
10. A braider carrier comprising a base member having a weight standard, a feed 60 control latch operatively mounted in said standard, a tension weight slidably mounted on said standard and having an extending portion adapted to engage a corresponding slot in said base to support said weight 65 against a lateral thrust of the stop motion when the weight drops to stop position.

In testimony whereof I affix my signature.

JOHN P. KING.
